UNITED STATES PATENT OFFICE

WILLIAM SCHWEMLEIN, OF PARKERSBURG, WEST VIRGINIA, ASSIGNEE TO THE PARKERSBURG RIG & REEL COMPANY, OF PARKERSBURG, WEST VIRGINIA, A CORPORATION OF WEST VIRGINIA

TANK SEAM

Application filed August 3, 1931. Serial No. 554,891.

This invention relates to storage tanks, and more particularly to a seam construction for the side plates of oil storage tanks.

It is the present practice to store oil in tanks of great capacity ranging upwardly from a capacity of 250 barrels. Such tanks usually are cylindrical and have their walls made up of steel plates the adjacent edges of which lie in overlapping relationship with an interposed packing strip, and are bolted together with closely arranged bolts which also pass through vertical channel irons which lend rigidity to the construction.

Such tanks are substantially satisfactory in use, although the seam joints of the tanks usually leak to some extent. Unless this leakage takes place to a material extent, no attention is paid to the leakage. The structure has the distinct further disadvantage, however, in that it requires a channel iron at each side seam, and each channel iron must be punched to provide bolt receiving openings, and since the bolts usually are arranged on two inch centers, it will be apparent that the structure requires the punching of a large number of openings for all of the channel irons. In addition to strengthening the structure, the channel irons have inwardly opening channels which receive the bolt heads and prevent the turning thereof, whereby the nuts on the outside of the tank may be tightened in the event excess leakage takes place.

An important object of the present invention is to provide a tank construction which possesses all of the rigidity of the prior constructions referred to, but wherein the use of channel irons and the necessity of punching openings therein are eliminated.

A further object is to provide a novel seam construction wherein the edge portions of the tank plates themselves are depended upon to provide the necessary rigidity and to provide means for preventing the turning of the bolt heads to permit the nuts of the bolts to be tightened from the outside of the tank when the latter is filled with oil.

A further object is to provide a seam structure of the character referred to which permits the packing employed to operate more efficiently, to prevent leakage from the tank

and to permit the use of securing bolts arranged a greater distance apart.

A further object is to provide an interlocking seam construction which is advantageous over prior constructions referred to in that each overlapping edge of a pair of adjacent sheets are stiffened, whereas in the usual constructions only the inner overlapping edge against the channel is stiffened while the other sheet is free to buckle between the bolts.

A further object is to provide an interlocking seam of the character referred to wherein the strength of the seam does not depend wholly upon the shear of the bolts alone but is greatly increased by the grip upon the interlocked portions of the sheets forming the side of the tank.

Other objects and advantages of the invention will become apparent during the course of the following description.

In the drawing I have shown several embodiments of the invention. In this showing:

Figure 1 is a fragmentary sectional perspective view of the adjacent edges of two tank plates, shown separated.

Figure 2 is an enlarged horizontal detailed sectional view through the seam and the associated elements.

Figure 3 is a similar view of a modified form of the seam structure, and,

Figure 4 is a similar view showing a further modification.

Referring to Figures 1 and 2, numeral 10 designates a pair of adjacent plates for the side wall of an oil storage tank. Each plate is provided at a point spaced from its vertical edge with a stamped or rolled offset portion 11 forming a rib for a purpose to be described. The outermost portions of the ribs may be joined to the body of the plates by sloping portions 12, although the exact shape of such portions is not of material importance. The ribs 11 are provided with spaced bolt receiving openings 13, as clearly shown.

A packing strip 14 is arranged between the overlapping edges of the sheets 10, and bolts 15 secure these overlapping edges toward each other with the packing 14 clamped therebetween. Each bolt includes a head 16 arranged within the tank, and a nut 17 ar-

ranged externally of the tank. It will be apparent that flat packing may be employed, and when the bolts are tightened, the packing takes the shape of the surfaces between which it is clamped. It will be apparent that the formation of the rib on the inner sheet 10 forms a channel 18 in which the bolt heads 16 are arranged.

In the form of the invention shown in Figure 3, side plates 19 and 20 are employed, the vertical edge of the plate 19 being arranged within the plate 20 and provided with spaced relatively narrow ribs 21 forming a channel 22 in which the bolt head is arranged. The bolt may be identical with the bolt previously described and need not be referred to in detail.

The formation of the ribs 21 forms small channels 23 between the adjacent faces of the plates 19 and 20. A compressible packing 24, preferably formed of rubber, is arranged between the overlapping portions of the sheets 19 and 20, and the tightening of the bolts deforms the packing so as to cause portions thereof to enter and fill the small channels 23, as clearly shown in Figure 3.

The form of the invention shown in Figure 4 is somewhat similar to Figure 3. Side plates 25 are employed, each of which is provided with spaced relatively narrow ribs 26, similar to the ribs 21 previously described, and the ribs of the inner plate 25 form a channel 27 to receive the bolt head. The ribs of the outer plate 25 correspond in position to the ribs of the inner plate 25, and accordingly the space in which the packing 28 is arranged is of substantially uniform width throughout the overlapping portions of the plates. The packing 28 obviously will be flexed around the ribs of the outer plate and into the ribs of the inner plate when the bolts are tightened.

The operation of the device will be apparent from the foregoing description. In each instance, flat compressible packing preferably is employed, and this packing is punched to receive the bolts 15. The openings of the inner and outer plates register with each other to receive the bolts, and the tightening of the bolts compresses the packing to prevent leakage. In assembling the tank, one mechanic inserts the bolts in the inside of the tank while the second mechanic on the outside of the tank applies and tightens the nuts. The tightening of the nuts compresses the packing and causes it to assume the shape of the space between the overlapping portions of the sheets. The deforming of the packing causes it to provide a far more efficient leak-proof joint than can be obtained with flat overlapping plates, and in actual practice it has been found that the bolts may be placed on three inch centers instead of two inch centers, as is the usual practice, and thus a saving is effected in the cost of the bolts and in the labor of applying them.

The ribs in each instance have been found to provide the vertical stiffening usually afforded by the channel irons, and these elements accordingly are eliminated with the consequent saving in material and in the cost involved in stamping bolt receiving openings in the channels. Moreover, the overlapping portions of the sheets are so altered in shape as to provide bolt head receiving channels whereby any leakage occurring in the tank, after it is filled, may be overcome by tightening the nuts 17, the channels for the bolt heads operating to prevent turning movement of the latter.

As previously stated, channels usually are employed for reinforcing the seams of tanks, and the channels are arranged against the inner face of the inner overlapping end of the tank sheet at each joint. Obviously the channel prevents inward buckling of the overlapping end against which it is arranged, but has no effect on the outer overlapping end, and accordingly leakage often occurs through the buckling of the outer sheet between the bolts. The present construction obviously eliminates this difficulty by preventing both sheets from buckling away from each other between the bolts. Moreover, the present tank constructions are made with relatively flat overlapping sheet ends, and accordingly the joints depend wholly upon the shear of the bolts for their strength. In the present construction, the bolts are assisted by the grip provided between the interlocking portions of the sheets, and thus a much stronger joint is provided.

From the foregoing it will be apparent that the present construction possesses all of the advantages of the prior constructions, and in addition possesses other advantages or importance. For example, a more efficient leak-proof joint is provided, and a considerable saving is effected in labor and material. Manufacturers often are called upon to furnish oil storage tanks on a short notice, and the present construction permits rapid manufacture due to the saving in time necessary for cutting the channel irons to lengths and punching openings therein, and after manufacture, the tanks may be more quickly set up due to the time saved through the elimination of the channel irons and the material reduction in the number of bolts employed.

While I have described in detail the preferred embodiment of my invention it is to be understood that various changes in the size, shape and arrangement of parts may be resorted to without departing from the spirit of the invention or the scope of the subjoined claims.

I claim:

1. A tank construction comprising a plurality of side plates each adjacent pair of which has its vertical edges overlapping and

provided with openings, one vertical edge portion of each plate being ribbed to reinforce the plate and to provide a vertical channel, and bolts arranged in the openings 6 of the plates and provided with heads corresponding in size to and arranged in said channels whereby the latter prevent turning movement of the bolts.

2. A tank construction comprising a plurality of side plates each adjacent pair of which has its vertical edges overlapping and provided with openings, one vertical edge portion of each plate being ribbed to reinforce the plate and to provide a vertical 15 channel, a compressible packing strip arranged between the overlapping edges of each pair of plates, and bolts arranged in the openings of the plates and projecting through each packing strip and adapted to 20 be tightened to clamp the overlapping edges of the plates together and to compress the packing to force it into the ribs of the plates, the heads of the bolts corresponding in size to and arranged in the channels of the plates 25 whereby the latter prevent turning movement of the bolts.

3. A tank construction comprising a plurality of side plates each adjacent pair of which has its vertical edges overlapping and 30 provided with openings, both vertical edge portions of each plate being ribbed to reinforce the plate with the ribs of the overlapping portions of the plates registering with each other, the ribs of the inward edge of 35 each plate defining a channel, and bolts projecting through the openings of the plates and provided with heads corresponding in size to and arranged in said channels whereby the latter prevent turning movement of 40 the bolts.

4. A tank construction comprising a plurality of side plates each adjacent pair of which has its vertical edges overlapping and provided with openings, both vertical edge 45 portions of each plate being ribbed to reinforce the plate with the ribs of the overlapping portions of the plates registering with each other, the ribs of the inward edge of each plate defining a channel, a compressible packing strip arranged between the overlapping edges of each pair of plates, and bolts arranged in the openings in the plates 50 and projecting through each packing strip, the heads of the bolts corresponding in size to and arranged in the channels of the plates 55 whereby the latter prevent turning movement of the bolts.

5. A tank construction comprising a plurality of side plates each adjacent pair of which has its vertical edges overlapping, each vertical edge portion of each plate being provided with an outwardly offset portion forming a rib of substantial width provided centrally of its width with a plurality 65 of openings, the rib of inner overlapping

edge of each plate defining a channel inwardly of the plate, and bolts projecting through the openings of the plates and provided with heads corresponding in size to and arranged in said channels whereby the 70 latter prevent turning movement of the bolts.

6. A tank construction comprising a plurality of side plates each adjacent pair of which has its vertical edges overlapping, 75 each vertical edge portion of each plate being provided with an outwardly offset portion forming a rib of substantial width provided centrally of its width with a plurality of openings, the rib of inner overlapping edge of each plate defining a channel inwardly of the plate, a compressible packing strip arranged between the overlapping edges of each adjacent pair of plates, and bolts projecting through the openings of the plates and through the packing strips and provided with heads corresponding in size to and arranged in said channels whereby the latter prevent turning movement of the bolts.

7. A tank construction comprising a plurality of side plates each adjacent pair of which has its vertical edges overlapping with the inner overlapping edge provided with a pair of spaced inwardly projecting ribs defining a channel, said overlapping edges being provided with openings lying in a plane between said ribs, a compressible packing strip arranged between the overlapping edges of each adjacent pair of plates, and bolts projecting through the openings of the plates and through the packing strips and provided with heads corresponding in size to and arranged in said channels whereby the latter prevent turning 105 movement of the bolts.

8. A tank construction comprising a plurality of side plates each adjacent pair of which has its vertical edges overlapping and provided in each edge with a pair of inwardly projecting ribs, said overlapping edges being provided with openings lying in a plane between said ribs, the ribs of the inner overlapping edges of the plates defining channels inwardly thereof, a compressible 110 packing strip arranged between the overlapping edges of each adjacent pair of plates, and bolts projecting through the openings of the plates and through the packing strips and provided with heads corresponding in size to and arranged in said channels whereby the latter prevent turning 120 movement of the bolts.

In testimony whereof I affix my signature.
WILLIAM SCHWEMLEIN.
